UNITED STATES PATENT OFFICE.

CHARLES H. FAWCETT, OF INDEPENDENCE, IOWA, ASSIGNOR TO INTERSTATE EVER-LICENSE COMPANY, OF INDEPENDENCE, IOWA.

LICENSE-HOLDER FOR MOTOR-VEHICLES.

1,328,915.

Specification of Letters Patent. Patented Jan. 27, 1920.

Application filed March 24, 1919. Serial No. 284,586.

To all whom it may concern:

Be it known that I, CHARLES H. FAWCETT, a citizen of the United States of America, and a resident of Independence, Buchanan 5 county, Iowa, have invented certain new and useful Improvements in License-Holders for Motor-Vehicles, of which the following is a specification.

My invention relates to improvements in license holders for motor vehicles, and the objects of my improvements are, first, to provide a closed hollow boxing or receptacle for a destructible license card, and from which the card cannot be removed without being so mutilated as to prevent its being altered for re-use; second, to provide said device with means for releasably locking a card therein, the locking device being releasable from the card only by the action 15 thereon of the special means provided for mutilating the card; third, to furnish a suitable slide carrier for the card, adapted to hold it in a suitable position in the boxing to be seen through the transparent top of the boxing, said carrier being of a form 20 adapted to coact with said locking means and to permit the cutting device to mutilate the card prior to the release of said locking means; fourth, to support the card within 25 said boxing adjacent to the path of movement of the cutting device to insure complete mutilation of the card by the cutting device.

With the foregoing and other objects in view which will appear as the description 35 proceeds, the invention resides in the combination and arrangement of parts and in the details of construction hereinafter described, and claimed, it being understood 40 that changes in the precise embodiment of invention herein disclosed can be made within the scope of what is claimed, without departing from the spirit of the invention.

In the drawings, Figure 1 is a top plan view of the complete device with the parts 45 of its boxing fixedly united together; Fig. 2 is a horizontal section of the device, taken on the broken line 2-2 of Fig. 3, looking 50 in the direction indicated by the arrow, showing the base plate projections raised; Fig. 3 is a vertical longitudinal section of the device, taken on the broken line 3-3 of said Fig. 2, looking in the direction indi-

cated by the arrow, but with the base-plate 55 projections sealed against the boxing flanges, and the card-cutting knife inserted within the boxing; Fig. 4 is a cross-section taken on the broken line 4-4 of said Fig. 2, and looking in the direction indicated by the 60 arrow, with the base-plate removed; Fig. 5 is a detail perspective view of the card-cutting knife, and Fig. 6 is an end elevation of the top part of the boxing, showing the movable escutcheon for the knife-inlet port. 65

Similar numerals of reference denote corresponding parts throughout the several views.

My device is contrived to safely hold a motor-vehicle license-card, and comprises a 70 closed hollow boxing, made up of a top part 1 of rectangular form, with open top 3 closed by a plate of glass 4 supported on brackets 5, and having an open bottom adapted to be closed by a base-plate 9, having 75 marginal projections 10 and 11 on its ends and sides to be folded over and fixedly united to marginal flanges 2 and 6 of the part 1 by means of solder strips 8. This sealing-means renders the boxing a secure 80 closed receptacle for the license-card 18, the latter being of cardboard or other like destructible material. The card 18 may contain on its upper face to be visible through the glass 4, such inscriptions as are suitable 85 for the purpose, and which will therefore not be specifically described, as Fig. 1 sufficiently discloses the nature of the inscriptions.

The box part 1 has inlet-ports at its opposite ends, one port 30 adapted to receive a rectangular slide 17, whose edges have upturned and inturned margins to detachably receive the edges of the card 18. The slide 90 is medially longitudinally slotted in line 95 with a vertical slot 29 or knife inlet-port in the opposite end of the boxing 1, and on the bottom of the slide is fixed a longitudinally troughed part 13 whose trough 23 is in registration with the slot in said slide and also 100 the port 29.

A cutting-device or knife 21, has a terminal oblique cutting end 22, and on its opposite end a stop projection 20 to limit its movement into the boxing through the port 105 29, and also has an orifice 25, to permit it to be hung up on a nail or other support when not in use.

An escutcheon plate 26 has a fixed pin 5 slidable in a slot 28 adjacent to the port 29, whereby said port may be covered to keep out dampness, when the knife is not in use, and has a knob 27 for operating it.

The slide 17 is slidable upon supporting brackets 7 fixed on the inner side walls of the boxing. A flat bar 24 is fixed in the upper part of the boxing longitudinally 10 along the under face of the glass 4 to abut upon the card 18 near and lengthwise of the slot in said slide, to afford an abutment, whereby when the knife 21 is moved through said slot its cutting edge 22 may sever the 15 card in twain preventing the card from buckling.

I have mounted a releasable locking device in the boxing to engage and lock the slide 17 therein, and prevent its removal 20 by any other means than the cutting-device or knife 21. This locking device comprises a pair of plate-springs 15 fixed on the boxing part 1 and extending toward and engaging with their free ends lugs 14 on the 25 bottom of the slide 17. The springs are fixedly connected by a cross-bar of triangular cross-section 16.

The card 18 being inserted in the engaging margins of said slide, the slide is moved 30 to its position in said boxing, and can only be removed as follows. The knife 21 is intruded through the port 29, its cutting edge 22 then slitting the card in two, and when the end of the knife reaches the triangular 35 bar 16, the bar rides over its edge, thus lifting the springs out of engagement with the lugs 14, so that the further progress of the knife can cause it to push the slide partially 40 out of the port 30, as far as permitted by engagement of the end of the trough 13 with the boxing, when the card may be removed, being cut into two parts, effectually mutilating 45 it to prevent its illegitimate alteration and reuse.

These license-card holders may be fastened upon a vehicle, and may be used year after year, the new cards issued being inserted after the mutilated card has been removed.

Having described my invention, what I claim as new, and desire to secure by Letters Patent, is:

1. In a device of the character described, a closed boxing having a card inlet port, 55 said boxing having a knife inlet port, and a disconnected knife-blade movable through the latter port and adapted to mutilate the card introduced into the boxing through said card inlet port.

2. In a device of the character described, a closed hollow boxing having a transparent top, said boxing having at opposite ends 60 inlet ports for a card and for a knife respectively, means within said boxing for supporting said card, and a disconnected

knife movable through a knife inlet port 65 removably and adapted to mutilate said card within the boxing.

3. In a device of the character described, a closed hollow boxing having a transparent 70 top, said boxing having inlet ports at its opposite ends, supporting means within the boxing, a card positioned upon said supporting means and removable through one of the inlet ports, means for releasably locking 75 said card within the boxing, and a knife movable through the other inlet port and adapted to first mutilate said card, and second, to release said card locking means, in succession.

4. In a device of the character described, a closed hollow boxing having a transparent 80 top, said boxing having inlet ports at its opposite ends, a slide having engaging means, and provided with a longitudinal 85 slot extending nearly its entire length, a card removably mounted on said slide over said slot and releasably secured in said engaging means, supporting means within said boxing, said slide being movable through 90 one of said inlet ports and supported upon said supporting means, a locking device within said boxing adapted to releasably lock said slide within the boxing, a knife adapted to pass through the other inlet port 95 movable through the slot in said slide and having an edged extremity adapted to split said card apart, said knife being positioned to engage said slide locking means near the end of its cutting stroke to release said 100 locking means from said slide.

5. In a device of the character described, a closed hollow boxing having a transparent top, said boxing having inlet ports at its opposite ends, a slide having engaging means, and provided with a longitudinal slot 105 extending nearly its entire length, a card removably mounted on said slide over said slot and releasably secured in said engaging means, supporting means within said boxing, said slide being movable through one of said inlet ports, and supported upon said supporting means, a locking device within 110 said boxing adapted to releasably lock said slide within the boxing, a knife adapted to pass through the other inlet port movable through the slot in said slide and having an edged extremity adapted to split said card apart, said knife being positioned to engage 115 said slide locking means near the end of its cutting stroke to release said locking means from said slide, said knife having a stop adapted to engage the boxing to limit its scope of movement therethrough.

6. In a device of the character described, 120 a closed hollow boxing having a transparent top, said boxing having inlet ports at its opposite ends, a longitudinal trough support within said boxing with its trough in alignment with one of said inlet ports, a slide 125 130

having card engaging means and movable into said boxing through the other inlet port, said slide when within the boxing being fixed upon said troughed element, and

5 having a longitudinal groove in registration with its trough, a card mounted on said slide, resilient locking means within said boxing adapted to releasably engage and lock the slide within the boxing, and an operating element movable through the first

10 mentioned inlet port, the trough of said supporting element and the slot of said slide, and adapted, first, to mutilate said card, and second, to engage and release said resilient locking device from said slide, to permit the latter to be withdrawn from the boxing with the mutilated card by way of the other inlet port.

7. In a device of the character described,

20 a closed hollow boxing having a transparent top, said boxing having inlet ports at its opposite ends, a longitudinal trough support within said boxing with its trough in alignment with one of said inlet ports, a slide

25 having card engaging means and movable into said boxing through the other inlet port, said slide when within the boxing being fixed upon said troughed element, and having a longitudinal groove in registration

30 with its trough, a card mounted on said slide, resilient locking means within said boxing adapted to releasably engage and lock the slide within the boxing, and an operating element movable through the first

35 mentioned inlet port, the trough of said supporting element and the slot of said slide, and adapted, first, to mutilate said card, and second, to engage and release said resilient locking device from said slide, to permit the latter to be withdrawn from the boxing with

the mutilated card by way of the other inlet port, and an abutment plate supported within said boxing against the inner side of its transparent top and positioned over said card adjacent to but not in registration with the slot in said slide to support the card while the latter is being mutilated by said mutilating means.

8. In a device of the character described, a hollow boxing having a closed transparent top, an open bottom, and a marginal flange around its open bottom extended outwardly, a base-plate secured over and covering said open bottom, means for supporting a card within said boxing in proximity to its transparent top, said boxing having an inlet port, and a disconnected cutting-device adapted to be inserted through said inlet port removably to mutilate said card.

9. In a device of the character described, a hollow boxing having a closed transparent top, an open bottom, and a marginal flange around its open bottom extended outwardly, a base-plate covering said open bottom, means for supporting a card within said boxing in proximity to its transparent top, said boxing having an inlet port, and a disconnected oblique-edged cutting-device adapted to be inserted through said inlet port to mutilate said card, means for locking said card releasably within the boxing, said means being located within the path of movement of said cutting device, and adapted to be engaged thereby and released from said card upon the completion of mutilation of the latter.

Signed at Waterloo, Iowa, this 21st day of March, 1919.

CHARLES H. FAWCETT.
